Attorney

UNITED STATES PATENT OFFICE

PETER E. SECKLER, OF TULSA, OKLAHOMA

HAND HOOK FOR PULL RODS

Application filed March 19, 1929. Serial No. 348,335.

This invention relates to hand hooks for pull rods or the like, employed in connection with oil well apparatus and is particularly adapted for use in connecting the pull rod 5 with a band wheel eccentric.

These hooks and their equivalents are relatively heavy and in placing them in operative position numerous accidents to operators have been met with.

10 An object of the present invention is to provide a hand hook of the type referred to of such construction as to practically eliminate accidents to operators in applying the hook in the desired operative position.

15 Another object is to provide a hand hook having a body portion through which a portion of the pull rod extends and in which one extremity of the pull rod is secured whereby only the hook portion of the device 20 need be connected while the band wheel is in operation.

25 A further object is to provide a device of the character referred to wherein the hook portion is pivotally mounted in the body portion and a hand grip is arranged on the hook portion to facilitate the handling thereof.

30 Other objects and advantages of the invention will become apparent during the course of the following description.

In the drawings I have shown one embodiment of the invention. In this showing,

Figure 1 is a side elevation,

Figure 2 is a plan view,

35 Figure 3 is a sectional view taken substantially on line 3—3 of Figure 1, and,

Figure 4 is a similar view taken substantially on line 4—4 of Figure 1.

40 Referring to the drawings, the numeral 10 designates as a whole the body portion of the device. This body portion is formed of a pair of complementary members 11 and 12 and each member is provided on opposite sides with relatively wide longitudinal reinforcing and securing portions 13. These securing portions 13 terminate at their outer ends in substantially rounded semi-annular reinforcing portions 14 and each member 11 and 12 is also provided with longitudinal

45 strengthening ribs 15. The inner faces of

the members 11 and 12 are provided with longitudinal substantially semi-annular grooves 16 and these inner faces are secured together whereby the grooves 16 will form a substantially annular opening. As shown, 55 bolts 17, extending through the securing portions 13, and nuts 18, may be used in securing the complementary members together.

60 The inner extremities 19 of the complementary members are partially cut away whereby an opening 20 is provided between the members when they are secured together, as shown in Figure 2. The extremities 19 are preferably rounded and provided with substantially central transverse openings 21.

65 The numeral 22 designates the hook portion of the device provided with a bill 23 at one extremity and a relatively wide portion 24 at its opposite extremity, the latter portion being provided with a central transverse opening 25 of substantially the same diameter as the openings 21. A shaft or pin 26 is secured in the opening 25 by means of the small pin 27 or the like, extending through the shaft and the portion 24. The ends of this shaft are adapted to be received in the openings 21, and the portion 24 extends into the opening 20 whereby the hook portion of the device will be pivotally connected to the body portion when the complementary members are secured together. 70 75 80

85 A hand grip 28 preferably formed integral with the hook portion is arranged on the upper side thereof to facilitate handling of the device.

86 The longitudinal opening in the body portion is adapted to snugly receive a pull rod 29 or the like, and the inner extremity of the pull rod is burred or otherwise suitably flattened substantially as shown at 30, whereby 90 the rod is firmly held by the body portion when the complementary members are secured together.

95 The bill 23 of the hook is adapted to engage a clevis 31 connected to a band wheel eccentric (not shown).

100 The operation of the device is believed to be apparent. When it is desired to connect the pull rod to the band wheel eccentric, the end of the rod is firmly secured in the body

portion of the device as described. The operator will then hold the body portion in one hand, grasp the hand grip 28 with the other hand and when the band wheel brings the 5 clevis 31 into position he engages the bill of the hook in the clevis thus completing the connection with a minimum of danger to his hands. The pivotal connection between the hook and body portion permits much free- 10 dom of movement of the hook by the operator in making the connection to the clevis.

The device is simple, may be economically constructed and quickly assembled, and securely connects the pull rod and band wheel 15 eccentric when in operative position.

It is to be understood that the form of the invention herewith shown and described is to be taken as a preferred example of the same and that various changes in the shape, 20 size and arrangement of parts may be resorted to without departing from the spirit of the invention or the scope of the subjoined claim.

I claim:

25 A device of the character described comprising a body portion formed of a pair of complementary members adapted to be secured together, each member being provided with relatively wide longitudinal reinforcing portions, said portions terminating at 30 their outer ends in substantially rounded semi-annular reinforcing portions, each member being further provided with a longitudinal strengthening rib arranged in spaced 35 relation to the said longitudinal reinforcing portions, each member being further provided with a longitudinal groove on its inner face, said grooves forming a longitudinal opening through said body portion, the inner face of each member being cut away adjacent one end of the body portion to provide 40 a slightly larger opening between said members communicating with said longitudinal opening, and a hook pivotally mounted in 45 said larger opening.

In testimony whereof I affix my signature.
PETER E. SECKLER.
